[57] CLAIM

The ornamental design for a “cartridge with camera for a game machine”, as shown and described.

DESCRIPTION

FIG. 1 is a top plan view of a cartridge with camera for a game machine in accordance with a first embodiment of my new design;

FIG. 2 is a left side elevation thereof;

FIG. 3 is a right side elevation thereof;

FIG. 4 is a bottom plan view thereof;

FIG. 5 is a front elevation thereof;

FIG. 6 is a rear elevation thereof;

FIG. 7 is a front right perspective view thereof;

FIG. 8 is a top plan view of a cartridge with camera for a game machine in accordance with a second embodiment of my new design;

FIG. 9 is a left side elevation thereof;

FIG. 10 is a right side elevation thereof;

FIG. 11 is a bottom plan view thereof;

FIG. 12 is a front elevation thereof;

FIG. 13 is a rear elevation thereof; and

FIG. 14 is a front right perspective view thereof.
